UNITED STATES PATENT OFFICE.

HENRY G. ELFBORG, OF CHICAGO, ILLINOIS.

GUARD-RAIL.

1,135,272.

Specification of Letters Patent. Patented Apr. 13, 1915.

Application filed April 6, 1911. Serial No. 619,296.

To all whom it may concern:

Be it known that I, HENRY G. ELFBORG, a citizen of the United States, residing at Chicago, in the county of Cook and State of Illinois, have invented certain new and useful Improvements in Guard-Rails, of which the following is a specification.

The object of my invention is to provide an improved guard rail for use in front of 10 facing point switches, opposite frog points and around curves for the purpose of guiding or deflecting wheel flanges to avoid derailment. While it is the general, in fact almost universal, practice at present to use a 15 piece of ordinary track rail spiked to the ties and sometimes held to the traffic rail by means of clamps, it is my purpose to construct a guard rail of cast metal, preferably manganese steel, and to form the casting 20 with integral parts adapted to coact with the traffic rail to hold the guard rail in proper relation thereto.

Other details of my invention will more clearly appear from the following description and claims, taken in connection with the accompanying drawings in which—

Figure 1 is a plan view of my improved guard rail in position opposite a traffic rail. Fig. 2 is a view of my improved guard rail 30 structure taken from the outer side thereof. Fig. 3 is an elevation of my improved guard rail taken from the inner side thereof, the words "inner" and "outer" being used to designate the side toward the center of the 35 track and the side away from the center of the track, respectively. Figs. 4, 5, 6 and 7 are transverse sectional views upon the dotted lines designated 4, 5, 6 and 7 upon Fig. 1. Fig. 8 is a perspective view of my improved 40 guard rail. Fig. 9 is a horizontal section on the line 9 of Fig. 7. Fig. 10 is a perspective view of a spacer or chuck which lies between the guard wall and the inner side of the traffic rail. Fig. 11 is a perspective view of 45 a wedge which lies between the rail clamp and the outer side of the traffic rail. Fig. 12 shows a fragment of the traffic rail in approximately correct relation to the chuck and wedge shown in Figs. 10 and 11, but 50 separated therefrom in order that the structure of the parts shown in these figures may be more clearly exhibited.

My improved guard rail structure comprises a base flange 1 and a substantially vertical guard wall 2 rising from the inner edge thereof. The upper part of the guard wall

2 may be provided with a head 3 of section somewhat similar to that upon the ordinary running rail, although this particular form may not in all cases be essential. At several 60 points along the length of the guard rail structure the guard wall 2 is provided with braces 4, each of these braces consisting of what may be conceived as an outward deflection of the guard wall 2, which slopes inwardly from the inner edge of the base flange 1 outwardly to the plane of the main body of the guard wall 2. The inclined sections 4 are joined to the main body of the guard wall 2 by transverse sections 5. The 65 entire structure as described is integral and the braces 4 afford means for supporting the guard wall 2 against the inward thrust of passing wheels. The base flange 1 may be secured to the ties by means of spikes 6 and 70 the parts are so proportioned that when assembled, as illustrated in the drawing, there is room between the base flange 1 of the guard rail structure and the inner base flange of the traffic rail for spikes 7 securing the traffic 75 rail in place. The ends of the guard wall are deflected outwardly in accordance with the usual practice and a horizontal web 8 may be formed integrally with the guard rail structure for the purpose of forming a 80 foot guard. As shown in Fig. 1, the horizontal web 8 extends across the space between the traffic rail 9 and the diverging end 85 of the guard rail structure. At its outer end the horizontal web 8 may be deflected downwardly, as indicated at 10, for the purpose of preventing the foot of a passerby from becoming wedged beneath the web 8.

In order to secure the guard rail in proper relation to the traffic rail, I provide the 90 guard rail with integral clamp members 11 projecting outwardly from the guard rail structure and adapted to underlie the traffic rail between adjacent ties. At its outer end each of the integral guide clamps 11 is provided with an upwardly extending projection 12 adapted to lie opposite the outer side of the traffic rail and a wedge 13 is driven 95 between the upward projection 12 and the outer side of the traffic rail 9 after the parts 100 are assembled.

Owing to the wear upon the face of the guard wall it becomes necessary after a period of use to adjust the guard rail structure to a point nearer the traffic rail in order to 110 reduce the width of the flange-way to the proper dimension. Adjustment is also nec-

essary to secure the proper width of flange-way upon curves. In order to secure a rigid structure it is desirable that some form of spacer or chuck be placed between the traffic rail and guard rail, and in order to provide for moving the guard rail to take up wear, it is necessary that the spacer or chuck used be of adjustable width, or that a plurality of chucks of different width be provided. In order to avoid the necessity of relying upon a plurality of chucks of different width, I provide the adjustable device shown in the drawings.

Upon the outer face of the guard wall I provide a projection 14 opposite each of the integral clamps 11-12. Upon its outer face the projection or lug 14 is corrugated or fluted as shown in the drawings. The chuck 15 is provided with a correspondingly corrugated or fluted face, and the fluted faces upon the members 14 and 15 lie along a plane inclined to the longitudinal dimensions of the traffic and guard rails. The inclination of this plane and the dimensions of the corrugations in the members 14 and 15 are so arranged and proportioned that by moving the member 15 longitudinally the distance of one corrugation its outer face will be moved a predetermined distance transversely of the rail, this predetermined distance being an eighth of an inch or a quarter of an inch or such distance as the fineness of adjustment requires.

The structure being assembled, as illustrated in Figs. 1, 5 to 7 and 9, it is retained in service until the flange-way becomes too wide owing to wear upon the guard wall, or when adjustment becomes necessary for other reasons. The wedge 13 is then driven out, the spikes 6 withdrawn, and the chucks 15 moved longitudinally (to the left as shown in Figs. 1 and 9) a distance of one or more corrugations according to the amount it is necessary to narrow the flange-way. The guard rail structure is then moved up snugly against the traffic rail to the required position and the wedge 13 again driven tightly in place. In order to secure the wedge in position after it is driven home, I have shown it as provided with a projecting fin 16 provided with a series of perforations 17 and have shown the upward projection 12 of the integral rail clamp provided with a notch 18 adapted to receive the fin 16. After the wedge 13 is driven home a cotter-pin 19 serves to secure it in place until another readjustment is necessary.

From the foregoing it will be apparent that I have provided a guard rail structure with integral clamps extending to the outer side of the traffic rail and with chucks or spacers and tightening wedges whereby separation of the guard rail structure from the traffic rail is impossible. Not only does this structure contain a minimum of separate

pieces, but the separate parts consisting only of the wedges and chucks are so arranged as to present the minimum possibility of displacement. I prefer to construct my improved guard rail of manganese steel owing to the great strength of this material, though it will be obvious that other materials might, under some circumstances, be substituted for manganese steel. While I have illustrated a form of guard rail adapted for use opposite a facing point switch, this particular form has been selected merely for the purpose of explanation and the structure described is equally adapted for use in connection with guard rails otherwise placed.

The foregoing description of a specific form of my improved guard rail structure and of adjustable spacer and tightening device is not intended as limiting my invention to the precise form shown and described, and my invention may be applied in various specific forms without departing from the principle thereof.

I claim:

1. In combination a guard rail structure and a traffic rail, said guard rail structure comprising a guard wall and a clamp integral therewith and extending beneath the traffic rail and having an upwardly extending projection adjacent the outer side of the traffic rail, a wedge between said projection and said traffic rail, said wedge having a projecting fin engaging a notch in said upwardly extending projection, a cotter-pin adapted to engage any one of a series of perforations in said fin, and an adjustable spacer between the inner side of said traffic rail and said guard wall.

2. A guard rail structure comprising a base flange, a guard wall comprising substantially vertical parts rising from the outer edge thereof and inclined parts rising from the inner edge thereof and inclining outwardly, said vertical and inclined parts being joined by transverse webs, and clamps integral with said guard wall.

3. In combination a guard rail structure and a traffic rail, said guard rail structure comprising a guard wall and a clamp integral therewith and extending beneath the traffic rail and having an upwardly extending projection adjacent the outer side of the traffic rail, said guard rail being provided with opposed inclined surfaces upon the inner side of said projection and upon the outer side of said guard wall respectively, wedges between said inclined surfaces and the web of the traffic rail and in contact with said web, and means for securing said wedges against displacement.

4. In combination a guard rail structure and a traffic rail, said guard rail structure comprising a guard wall and a clamp integral therewith and extending beneath the traffic rail and having an upwardly extend-

ing projection adjacent the outer side of the traffic rail, said guard rail being provided with opposed inclined surfaces upon the inner side of said projection and upon the 5 outer side of said guard wall respectively, wedges between said inclined surfaces and the web of the traffic rail and contact with said web, one of said wedges and the coacting inclined surface being corrugated and 10 the other wedge and incline having coacting

substantially plane surfaces, and means for securing the latter wedge against displacement.

In testimony whereof, I have subscribed my name.

HENRY G. ELFBORG.
